UNITED STATES PATENT OFFICE

PHILIP B. ROHNER, OF CARROLL, IOWA

RAG RIPPER

Application filed March 14, 1929. Serial No. 346,997.

This invention relates to a device for ripping rags into strips such as might be used in the weaving of carpets, rugs and the like, or for any desirable purpose.

5 Rags as collected will be of various shapes and sizes, and before they can be used, for most purposes it is desirable to form them into uniform strips of a predetermined width and accordingly an object of this invention is the provision of means to quickly and easily cut or rip one rag after another into strips of the same width, regardless of the direction of the weave or grain of the cloth.

10 15 Varying uses and conditions may necessitate a variation in the width of the strips and another object of this invention is the provision of means to easily measure the width of strip desired and cut the cloth to this measurement.

It is also an object of this invention to provide a measuring gage which functions in use as a guide for the strip as it is being cut, which gage is adjustable instantly.

20 25 A further object is the provision of a structure in which a razor blade may be utilized as the ripping or cutting medium, and the device is so designed as to accommodate any make, shape or form of safety razor blade as a cutting tool, by making a very slight adjustment.

The device also may readily be used as a seam or thread ripper, or for many other purposes, either with or without the guide.

30 35 To the attainment of these and other objects there are provided certain arrangements and combinations of parts hereinafter described and more particularly pointed out in the appended claims. Reference is to be had to the accompanying drawings, in which:

Figure 1 is a diagrammatic view of the invention, in perspective, showing the manner of its use,

40 45 Figure 2 is a plan view showing the relative position of the several parts,

Figure 3 is a section on the line 3—3 of Figure 2,

50 55 Figure 4 is a sectional view partly in elevation illustrating a slightly modified form of invention.

It will be observed that a frame or body 5 is provided with a shoulder 6 on its lower side for positioning the body on any suitable support as a table or bench to which it may be clamped by a clamp 7.

55 The top of the body may be skived or flattened as at 8 to form a thinner portion suitable for engagement by the clamp.

A suitable guide such as a groove 9 or other tracking means is provided along at least one side of the body, with which is engageable a flange 10 of a slidible member 11. This member is adapted to form a guide for the rags as they are ripped, and to this end is provided with an upstanding abutment or gage element 12 against which the rag edge is placed as indicated in Figure 1.

60 65 Finger pieces 13 are illustrated at one end of the slidible member and form a means of manipulating the member when setting the gage for different widths of strips. The member 11 may be held in position by any desirable means, as friction, but if made of spring metal, will retain its position by inherent tension of the flange 10, positioned in 70 groove 9. If desired, a set screw might be used to hold the member in position.

75 The body 5 may be provided with a section 14, separable therefrom and which is held in place to complete the body by a bolt or screw 80 15 passing through the section into the body.

With this construction it will be obvious that if a razor blade 16 is positioned between the section 14 and the adjacent portion of the body 5, the blade can be clamped in position 85 by forcing the screw 15 home.

Another way of mounting the blade is shown in Figure 4, in which the body 5 is slotted as at 17. The blade is dropped into the slot and clamped by a screw 18.

90 95 Regardless of mounting, however, the blade will have one end projecting above the body 5 and member 11, the latter being cut away as at 19, for the purpose. The edge of member 11 along the cut out may be graduated if desired.

In the use of the device, the body 5 is clamped to the table or support, the member 11 is positioned to locate the gage 12 for a desired width and a rag 20 is placed against 100

the gage, and drawn past the cutting edge of the blade. It will be seen that a rag can thus be ripped with straight edges, no matter in what direction the weave or grain runs, and 5 that any predetermined width of strip may be obtained, with an assurance of uniformity in successive strips.

When a blade loses its utility, it is but a simple matter to substitute another blade in its 10 stead, and any type of blade may be used.

The device is also handy as a means of 15 ripping seams, cutting threads, etc., it being unnecessary in some instances to use the gage and guide member. This invention is capable 20 of a variety of uses and modifications and it is not intended that same shall be limited except as hereinafter claimed.

Having thus described my invention, what I claim as new and desire to secure by Letters 25 Patent of the United States is:—

1. In a device for ripping rags, the combination of a body member and a cutting member, said body member having a detachable portion effective to engage said cutting member and clamp same in the body member, 25 and a guide movable on said body member relative to said cutting member, effective to guide a rag strip as it is ripped, said guide having a rounded surface adapted to project 30 under the strip to facilitate movement of the strip, and gauging means on said projection.

2. In a rag ripping device, a body having 35 a slot therein, and a groove therealong, a cutter located in said slot, means to clamp said cutter in the slot, a guide slidable on said body relative to said cutter, means on said guide engageable with said groove, and means to move said guide along the groove, said guide having a rounded surface adapted 40 to project under the strip to facilitate movement of the strip, and being graduated along an edge adjacent said cutter.

3. In a device for ripping rags, a body, 45 means to fasten said body to a support, a cutter, means to attach said cutter to said body, a carriage slidable along said body and having a portion adapted to project under a rag to be ripped, a calibrated gauge arranged 50 on said portion, said portion having a slightly rounded surface and means to move said gage relative to said cutter, whereby a rag drawn over said body will be ripped by said cutter to a predetermined width and will be 55 guided by said gage, to produce a straight edge.

4. In a device of the character described, 60 a body member including a cutter, a carriage movable on said body member toward and from said cutter having a portion extending transversely of said cutter, means on said carriage effective to guide a strip of material passed over said body member, gauge means on said portion, cooperative with said cutting member to indicate the location of said guid-

ing means, said carriage, guide means and gauge means being arranged as a unit.

5. In a device of the character described, 70 a body member and a cutting member, means to detachably clamp said cutting member in said body member, a carriage formed of substantially rigid sheet material slidable along said body member relative to said cutting member, said carriage having an upstruck lug effective to guide a strip of material 75 passed over said body member, and means to adjust said lug to a predetermined position relative to said cutting member.

6. In a device of the character described, 80 a body member and a cutting member, means to detachably clamp said cutting member in said body member, a carriage formed of substantially rigid sheet material slidable along 85 said body member relative to said cutting member, said carriage having an upstruck lug effective to guide a strip of material passed over said body member, and means to adjust said lug to a predetermined position relative to said cutting member, and means to clamp said body member to a support.

7. In a device of the character described, 90 a substantially cylindrical, elongated body member, a cutting member mounted therein and adjacent one end thereof, a carriage partially encompassing said body member and 95 slidable therealong, said carriage having a portion cooperative with said cutting member to predetermine the width of a strip to be cut.

8. In a device of the character described, 100 an elongated body member, a cutting member mounted therein and adjacent one end thereof, a carriage partially encompassing said body member and slidable therealong, said carriage having a projecting portion extending lengthwise of the body member and movable past the cutting edge of the cutting member, said carriage having an abutment extending outwardly from said body and cooperative with said cutting member to predetermine the width of a strip to be cut, and 105 gauging means located on said projecting portion.

9. In a device of the character described, 110 an elongated body member having at one end a shoulder and an arm extending beyond said shoulder, said arm and shoulder providing means to position said body member on a support, a cutting member mounted adjacent the other end of said body member, and a 115 gauge movable between said shoulder and cutter to predetermine the width of a strip to be cut.

10. In a device of the character described, 120 an elongated body member having at one end a shoulder and an arm extending beyond said shoulder, said arm and shoulder providing means to position said body member on a support, a cutting member mounted adjacent the other end of said body member, means op- 125

erable from the latter end of the body to detachably clamp said cutting member in position, and a gauge movable between said shoulder and cutter to predetermine the width of a strip to be cut.

5 11. In a device of the character described, a body member having a cutting member extending therein with a cutting edge projecting thereabove, a carriage member slidable along said body member and having a portion 10 extending in front of said cutting member, said carriage member having an abutment extending outwardly from said body member and effective to guide a strip of material to be cut, and means on said portion 15 to indicate the position of said abutment relative to said cutting member.

12. In a device of the character described, a body member having a cutting member extending therein with a cutting edge projecting 20 thereabove, a carriage member slidable along said body member and having a portion extending in front of said cutting member, said carriage member having an abutment 25 extending outwardly from said body member and effective to guide a strip of material to be cut, and means on said portion to indicate the position of said abutment relative 30 to said cutting member, and a lug extending from said carriage to move the same along said body member.

13. In a device of the character described, a body member having a semi-cylindrical surface, a cutting member positioned adjacent one end thereof, a groove extending 35 along said body member adjacent said surface, and a carriage fitting said surface and having an inturned flange slidable in said groove, said carriage being provided with means to guide a strip of material to be cut 40 past the cutting member.

In testimony whereof I hereunto affix my signature.

PHILIP B. ROHNER.
